COPYING MACHINE OR SIMILAR ARTICLE

Charles E. Jones and Joseph H. Gruenhut, Lincolnwood, Ill., assignors to Bell & Howell Company, Chicago, Ill., a corporation of Illinois

Filed July 7, 1967, Ser. No. 7,726

Term of patent 14 years

U.S. Cl. D61—1
Int. Cl. D18—03

FIGURE 1 is an isometric view of a copying machine or similar article embodying our new design.

FIGURE 2 is a side elevational view showing the side hidden in FIGURE 1.

FIGURE 3 is a front elevational view of the design shown in FIGURE 1.

The rear and underneath panels are unornamented and are generally rectangular in configuration as will be apparent from an inspection of FIGURE 2.

We claim:

The ornamental design for a copying machine or similar article, as shown and described.
